UNITED STATES PATENT OFFICE.

FRANCIS McMAHON, OF SOMERVILLE, MASSACHUSETTS.

SUBMARINE VIEWING APPARATUS.

SPECIFICATION forming part of Letters Patent No. 783,730, dated February 28, 1905.

Application filed April 19, 1904. Serial No. 203,916.

To all whom it may concern:

Be it known that I, FRANCIS McMAHON, of Somerville, in the county of Middlesex and State of Massachusetts, have invented certain 5 new and useful Improvements in Submarine Viewing Apparatus, of which the following is a specification.

This invention has for its object to provide an apparatus adapted to permit an inspection 10 of submerged surfaces, such as the beds of rivers and other bodies of water or the surfaces of sunken vessels, &c.

The invention consists in the improvements which I will now proceed to describe and claim.

15 The accompanying drawing represents a side elevation, partly in section, of an apparatus embodying my invention.

a represents a sight-tube having at one end a lens *b*', which is preferably fitted in an enlargement *a'* of the tube. Said enlargement may have two or more lenses, if desired. The tube is of suitable length to extend from above the surface of a body of water to a point near the bottom or other submerged object to be 25 viewed, so that an observer above the surface may apply his eye to the upper end of the tube and view the said object.

b represents an electric lamp, which may be of ordinary construction. *c* represents a 30 holder for said lamp, which is adapted to exclude water from the lamp and is suitably connected with the tube *a*, so that the whole may be moved together into and out of the water. The preferred connection between 35 the tube and lamp-holder comprises a standard *d*, arms *d'* *d''*, connecting the standard with the tube, and arms *d''* *d'''*, connecting the standard with the lamp-holder. The arms *d''* may be adjustably secured to the standard, said 40 arms being formed to be clamped upon the standard by means of bolts *e*. The lamp-holder comprises a transparent section 2, preferably a glass globe, which protects the bulb 3 of the lamp, a flexible section 4, which incloses the mouth of the section 2 and the lamp-socket 5, and a tubular flexible section 6, which incloses the circuit-wires 7 and is attached 45 to the sight-tube. The upper portion of the flexible section covering the lamp-switch 8 is sufficiently flexible to permit the turning of

the switch, the said portion being pressed against the switch by the operator's thumb and finger and moving with the switch when the latter is turned.

When the described apparatus is lowered 55 into a body of water, the lamp illuminates the region adjacent to the lens, the lower end of the standard limiting the downward movement of the apparatus by coming in contact with the bed of the river or other body of 60 water or the surface to be inspected. The observer at the upper end of the sight-tube is therefore enabled to conveniently inspect the illuminated region. Owing to the standard *d* being out of alinement with the sight-tube, 65 said standard offers no obstruction to the view of the bed of the river or other surface to be inspected.

I do not limit myself to the details of construction here shown and described, and the 70 same may be variously modified without departing from the spirit of the invention.

The sight-tube may be composed of sections detachably connected, so that the tube as a whole may be made of any desired length. 75 I prefer to make each section about six feet long and provide it with screw-threads or other means for coupling it to another section. The sight-tube is, however, non-adjustable in length when in use, having no parts 80 which are in sliding contact with each other.

All parts of the apparatus which are submerged are immovably connected, and therefore they can be and are constructed so as to be absolutely water-tight throughout, which 85 could not be the case if the tube were made of sections slidably, and therefore movably, connected. Moreover, said immovable connection of the parts prevents any disturbance of their relative arrangements or positions by 90 movement of the water or any effect of buoyancy.

I claim—

1. An apparatus of the character stated, comprising a sight-tube provided with a lens 95 immovable relatively to the upper portion of the tube, an electric lamp adjacent to the lens and at one side of and connected with the tube, said tube and lamp being adapted to be inserted in a body of water, and means for 100

limiting downward movement of the apparatus, said means being located at one side of the line of sight through the tube and lens whereby a direct view downward through the tube and lens will not be obstructed by said limiting means.

2. An apparatus of the character stated comprising a sight-tube provided with a lens, a water-tight lamp-holder having a transparent section, an electric lamp inclosed in said holder, the said holder having a tubular extension inclosing the circuit-wires of the lamp, and a standard projecting downward below the lower end of the sight-tube and at one side thereof to limit downward movement of the apparatus, all of the parts being immovably connected.

3. An apparatus of the character stated, comprising a sight-tube provided with a lens, an electric lamp, a water-tight lamp-holder having a transparent section covering the bulb of the lamp, a flexible section covering the socket and switch of the lamp, a flexible tubular section inclosing the circuit-wires, and means for limiting downward movement of the apparatus without obstructing the view through the tube all of the parts being immovably connected.

In testimony whereof I have affixed my signature in presence of two witnesses.

FRANCIS McMAHON.
